MOBILE BUNGY JUMP APPARATUS AND METHOD FOR OPERATING THE SAME

CROSS-REFERENCE TO RELATED APPLICATION

This application claims benefit of priority of Singapore Patent Application No. 10202260007T, entitled "MOBILE BUNGY JUMP APPARATUS AND METHOD FOR OPERATING THE SAME," filed Nov. 8, 2022. The entire content and disclosure of this patent application is incorporated herein by reference in its entirety.

TECHNICAL FIELD

Various embodiments relate to a bungee jump apparatus, and more particularly, a mobile bungee jump apparatus and a method of operating the mobile bungee jump apparatus.

BACKGROUND

Bungee jumping, also known as bungee jumping, is a popular adventure sport and has been commercially operated for about 30 years. In bungee jumping, a bungee jumper jumps off a tall structure, such as a building, bridge, natural geographic feature, or crane, onto which a bungee jumping platform is erected for locating and fixing the bungee jump equipment and accommodating the bungee jumper and operation personnel.

Commercial bungee jumping platforms that are fixed on/to tall infrastructures or natural geographic features are usually time-consuming and costly to construct. The construction of bungee jumping platforms on these structures can also create obstructions that are not acceptable for long periods of time or cause damages that are not reversible.

Additionally, the commercial bungee jumping platforms will also have varied popularity, depending on proximity to other sites, time of the year, age of the site, and various other factors. Therefore, some platforms can only be open for a limited time in a year, which results in inefficient use of the bungee jumping equipment and personnel.

To address the above issues, there is a need for an apparatus and a method that may eliminate or at least minimize obstructions or damages to the jumping structures and may be relocated according to the seasonal popularity conveniently and may reduce the complexity of relocating, setting up, and operating a bungee jumping platform in terms of the time and labor required.

SUMMARY OF INVENTION

Embodiments of the invention provide for a mobile bungee jump apparatus that comprises a wheeled vehicle, e.g. truck, and a jump-off platform carried by the wheeled vehicle through a retractable apparatus coupled to the wheeled vehicle, wherein the jump-off platform is configured to at least move between a non-bungee jumping position and a bungee jumping position, and wherein the retractable apparatus includes a jump-off platform and a rigging frame or equivalent to which a bungee cord tethering a bungee jumper may be attached.

According to an embodiment, a mobile bungee jump apparatus is provided. The mobile bungee jump apparatus may include a wheeled vehicle chassis, a retractable apparatus mounted on the wheeled vehicle chassis for providing a jump-off platform with a first stowed position for transportation, or a first extended position for off-bridge access.

2

The jump-off platform may be movably coupled to the retractable apparatus and storable substantially within a footprint of the wheeled vehicle chassis when the jump-off platform is in the first stowed position, and extendable from the retractable apparatus when the jump-off platform is in the first extended position for bungee jumping. A rigging frame is fixedly coupled to the jump-off platform and configured to be secured to an end of a bungee cord having another end securable to a bungee jumper.

Advantageously, the bungee jumping apparatus may require less labor to relocate, set up, and operate and may provide better stability in both transporting and operating processes and may take a smaller footprint in a bungee jumping site.

According to an embodiment, a method of operating a mobile bungee jumping apparatus is provided. The method may include: arranging the mobile bungee jumping apparatus at a current bungee site while maintaining the retractable apparatus in a second stowed position; arranging the jump-off platform in a first extended position for bungee jumping; securing an end of a bungee cord to the rigging frame and secure another end of the bungee cord to a bungee jumper; facilitating the jumping of the bungee jumper from the jump-off platform.

Advantageously, the method of operating the mobile bungee jumping apparatus may require less labor to operate the apparatus stably and safely.

BRIEF DESCRIPTION OF DRAWINGS

In the drawings, like reference characters generally refer to like parts throughout the different views. The drawings are not necessarily to scale, emphasis instead generally being placed upon illustrating the principles of the invention. In the following description, various embodiments of the invention are described with reference to the following drawings, in which:

FIG. 1 is a schematic diagram illustrating a mobile bungee jump apparatus, according to various embodiments.

FIG. 2A is a schematic diagram illustrating a top view of an exemplary mobile bungee apparatus in a stowed position, according to various embodiments.

FIG. 2B is a schematic diagram illustrating a side view of the exemplary mobile bungee apparatus of FIG. 2A, according to various embodiments.

FIG. 2C is a schematic diagram illustrating a rear view of the exemplary mobile bungee apparatus of FIG. 2A, according to various embodiments.

FIG. 3 is a schematic diagram illustrating the exemplary mobile bungee apparatus of FIG. 1C on a cross-sectional view of a bridge, according to various embodiments.

FIG. 4 is a schematic diagram illustrating a rear view of an exemplary mobile bungee apparatus on a cross-sectional view of a bridge, in which portions of the mobile bungee apparatus are in extended positions to provide a bungee jumper with an off-bridge jump-off platform, according to various embodiments.

FIG. 5 is a flow chart illustrating a method of operating a mobile bungee apparatus of FIG. 2A to 2C and FIG. 9A to 9C, according to various embodiments.

FIG. 6 is a schematic diagram illustrating a rear view of the exemplary mobile bungee apparatus of FIG. 4, in which a bungee jumper is in a cord retrieval process, according to various embodiments.

FIG. 7 is a schematic diagram illustrating a top view of the exemplary mobile bungee jump apparatus of FIG. 4, according to various embodiments.

FIG. 8 is a schematic diagram illustrating the details of the extendable portions of the exemplary mobile bungey jumping apparatus of FIG. 4, according to various embodiments.

FIG. 9A is a schematic diagram illustrating a top view of another exemplary mobile bungey jump apparatus in a stowed position, according to various embodiments.

FIG. 9B is a schematic diagram illustrating a front view of the exemplary mobile bungey jump apparatus of FIG. 9A, according to various embodiments.

FIG. 9C is a schematic diagram illustrating a rear view of the exemplary mobile bungey jump apparatus of FIG. 9A, according to various embodiments.

FIG. 10 is a schematic diagram illustrating the exemplary mobile bungey jump apparatus of FIG. 9C on a cross-sectional view of a bridge, according to various embodiments.

FIG. 11 is a schematic diagram illustrating a side view of another exemplary mobile bungey apparatus in an extended position, according to various embodiments.

FIG. 12 is a schematic diagram illustrating a rear view of the exemplary mobile bungey jump apparatus of FIG. 11 on a cross-sectional view of a bridge, in which a bungey jumper has jumped off an extended jump-off platform, according to various embodiments.

DETAILED DESCRIPTION

The following detailed description refers to the accompanying drawings that show, by way of illustrations, specific details and embodiments in which the invention may be practiced. These embodiments are described in sufficient detail to enable those skilled in the art to practice the invention. Other embodiments may be utilized and structural, logical, and electrical changes may be made without departing from the scope of the invention. The various embodiments are not necessarily mutually exclusive, as some embodiments can be combined with one or more embodiments to form new embodiments.

Embodiments described in the context of one of the methods or apparatus are analogously valid for the other methods or apparatus. Similarly, embodiments described in the context of a method are analogously valid for an apparatus, and vice versa.

Features that are described in the context of an embodiment may correspondingly be applicable to the same or similar features in the other embodiments. Features that are described in the context of an embodiment may correspondingly be applicable to the other embodiments, even if not explicitly described in other embodiments. Furthermore, additions and/or combinations and/or alternatives described for a feature in the context of an embodiment may correspondingly be applicable to the same or similar feature in the other embodiments.

In the context of various embodiments, the articles “a”, “an”, and “the” as used with regard to a feature or element include a reference to one or more of the features or elements. The terms “comprising”, “including”, “having”, and any of their related terms, as used in description and claims, are intended to be open-ended and mean that there may be additional features or elements other than the listed ones.

As used herein, the phrase of the form of “A and/or B” may include A or B or both A and B.

In the context of various embodiments, the phrases “configured to”, “arranged to”, “constructed and arranged to” and “adapted to” may be used interchangeably.

Although the terms first and second may be used herein to describe various stowed positions and extended positions, these positions should not be limited by these terms. These terms may be only used to distinguish one position from another position. Terms such as “first”, “second”, and other numerical terms when used herein do not imply a sequence or order unless indicated by the context. In the following context, the term “first” generally refers to the jump-off platform, and the term “second” generally refers to the retractable apparatus.

In the context of various embodiments, the term “modified” may include both reversible and non-reversible modifications.

Various embodiments may provide a bungey jump apparatus. For example, the bungey jump apparatus may non-labor intensively set up a bungey jump platform at an elevated but limited bungey jump space, e.g., a bridge or a cliff, for a bungey jumper and provide a safe place for accommodating the bungey jump equipment and personnel.

Various embodiments may provide a method of operating a bungey jump apparatus, for example, the steps of setting up the bungey jump location for a bungey jumper to jump off and recover.

FIG. 1 is a schematic diagram illustrating a mobile bungey jump apparatus 100, in accordance with various embodiments. As seen in FIG. 1, the mobile bungey jump apparatus 100 may include a wheeled vehicle chassis 102, a retractable apparatus 104, a jump-off platform 106, and a rigging frame 108. The retractable apparatus 104 may be mounted on the wheeled vehicle chassis 102 for providing the jump-off platform 106 with a first stowed position for transportation or a first extended position for off-bridge access. The jump-off platform 106 may be movably coupled to the retractable apparatus 104 and storable substantially within a footprint of the wheeled vehicle chassis 102 when the jump-off platform 106 is in the first stowed position, and extendable from the retractable apparatus 104 when the jump-off platform 106 is in the first extended position for bungey jumping. The rigging frame 108 may be fixedly coupled to the jump-off platform 106 and configured to be secured to an end of a bungey cord (e.g. 119 in FIG. 4) having another end securable to a bungey jumper (e.g. 118 in FIG. 4).

Referring to FIG. 1 and parts of FIGS. 2A to 12, the wheeled vehicle chassis 102 may be modified or adapted from any type of vehicle that may be self-propelling or movable, which may provide the mobile bungey apparatus 100 with flexibility in mobility with less labor involved. The wheeled vehicle chassis 102 may be driven or hauled to a target bungey jumping site. This in turn eases the transportation of apparatus 100 and, therefore, allows the apparatus 100 to utilize the height of natural or man-made structures, such as cliffs or bridges. The wheeled vehicle 102 may accommodate a retractable apparatus 104 for providing a jump-off platform 106. The phrase “accommodate a retractable apparatus 104” may refer to mechanical engagement that may attach the retractable apparatus 104 on top of the wheeled vehicle chassis 102. The retractable apparatus 104 may be arranged in a position extended from the edge of the footprint of the wheeled vehicle 102 for off-bridge access, or it may be arranged in a position within the footprint of the wheeled vehicle 102 for transportation. Such an extended position of the retractable apparatus 104 may provide a bungey jumper with an extended jump-off platform 106 for a bungey jump, while such a stowed position of the retractable apparatus 104 may provide the apparatus 100 with a compact arrangement in relocation.

The jump-off platform 106 may be coupled to the retractable apparatus 104 in a fixed or an unfixed manner. In one example, the movement of jump-off platform 106 may result from the movement of the retractable apparatus 104. When the retractable apparatus 104 is in an extended position, the jump-off platform 106 may accordingly be in an extended position to provide off-bridge access. In another example, the jump-off platform 106 may be rotatably coupled to the retractable apparatus 104 to be able to extend relative to the edge of the wheeled vehicle chassis 102 to provide an extended position for off-bridge access.

The rigging frame 108 may be fixedly coupled to the jump-off platform 106 to secure a safe bungey jumping in a manner of a safety cord having one end attached to the bungey jumper and the other end attached to the rigging frame 108 directly.

FIG. 2A, FIG. 2B, and FIG. 2C show schematic top, side, and rear views, of a mobile bungey apparatus 200 in a stowed position, respectively. With reference to FIG. 1, the wheeled chassis (e.g. 102 in FIG. 1) in FIGS. 2A to 2C is adapted from a truck, and the retractable apparatus (e.g. 102 in FIG. 1) is configured to be arranged in a second stowed position when the jump-off platform (e.g. 104 in FIG. 1) is configured to be arranged in a first stowed position for transportation. Advantageously, such a compact configuration of the apparatus 200 is arranged for transportation/relocation.

FIG. 3 shows a schematic rear view of a mobile bungey apparatus 200 of FIG. 2C on a cross-sectional view of a bridge 300. As aforementioned, the movement of the jump-off platform 206 may result from the movement of the retractable apparatus 204. Therefore, when the retractable apparatus 204 may be configured to be arranged in a second stowed position, the jump-off platform 206 may thus be configured to be arranged in a first stowed position. As seen in FIG. 3, apparatus 200 may utilize the height of bridge 300 to provide a proper bungey jumping site. In FIG. 3, wheeled vehicle chassis 202 may be modified or adapted from a bridge inspection truck. Advantageously, it may provide flexibility and access to limited or narrowed bungey jumping locations. Moreover, a bridge inspection truck modified vehicle chassis 202 may require less labor to operate, transport, and yet provide a proper bungey jump location without causing any damage to the tall structure onto which the apparatus 200 may be at. The angles of the joints of the retractable apparatus 204 may be maximally folded to maintain the retractable apparatus 204 in the second stowed position and the jump-off platform 206 in a first stowed position, which allow the mobile bungey apparatus 200 to move stably.

In one example, the retractable apparatus 204 may be a modified or adapted portion of a boom truck, a truck mounted with an aerial platform, or any suitable truck. One advantage of the modified retractable apparatus 204 of a bridge inspection or other suitable truck is to provide its attached bungey jump platform jump-off platform 206 with flexible access to bungey jump sites, especially for off and/or under-bridge bungey jumping locations.

In another example, the retractable apparatus may be purpose-designed and manufactured for bungey jumping.

In yet another example, the bungey jumping site may be a bridge, a cliff, or any locations having a great height at which a mobile bungey apparatus may be driven or transported or hauled and stably located.

FIG. 4 shows a schematic rear view of a mobile bungey apparatus 200 on a cross-sectional view of a bridge 300. In FIG. 4, the position of the jump-off platform 206 may be referred to as a first extended position, and the position of the

retractable apparatus 204 may be referred to as a second extended position. Thus, the retractable apparatus 204 is configured to be arranged in a second extended position when the jump-off platform 206 is in a first extended position for bungey jumping. The vehicle chassis 202 and a portion of the retractable apparatus 204 remain on the bridge 300, and portions of the retractable apparatus 204 are in a second extended position 108, thus providing a bungey jumper 118 an off-bridge jumping-off location. The term "off-bridge" may refer to positions that are spacially apart from the bridge where elevated locations can be provided for a bungey jump. The off-bridge locations may include but are not limited to the spaces under the bridge, outside the edge of the bridge, or above the bridge. The phrase "outside the edge of the bridge" may refer to positions that are not directly under or above the bridge.

As seen in FIG. 4, the retractable apparatus 204 may include at least two sections: an intermediate section 210 extendable or retractable relative to the wheeled vehicle chassis 202 and an end section 212 movably coupled to the intermediate section 210. The end section 212 may be movably coupled to a jump-off platform 206. In one example, the jump-off apparatus 204 may be slidably coupled to the end section 212, such that the end section 212 of the retractable apparatus 204 together with the jump-off platform 206 are in an off-bridge position, which provides a location for a bungey jumper 118 to start a bungey jump. The end section 212 of the retractable apparatus 204 may also provide a secure space for bungey staff 124 to operate the bungey jumping equipment. The jump-off platform 206 is where a bungey jumper 118 may jump off and, optionally, return after completing a jump. One advantage of having one or more sections in a retractable apparatus 204 is to allow more positions of the retractable apparatus 204 suitable for various situations. In transportation, the retractable apparatus 204 can be folded stably, while in preparation for the jump-off platform 206, the sections may be extended to provide enough space for a bungey jump.

In one example, the jump-off platform 206 may be fixedly or movably coupled to the end section 212 of the retractable apparatus 204.

In yet another example, the jump-off platform 206 may be slidably onto the end section 212 of the retractable apparatus 204. Advantageously, a slidably coupled jump-off platform 206 may be retracted to stack on top of the end section 212 of the retractable apparatus 204 for saving space and increasing stability or be extended relative to the end section 212 to provide a safe and/or comfortable space for a bungey jump.

A rigging frame 208 may be fixedly coupled to the jump-off platform 206 and configured to be secured to one end of a bungey cord 119 having another end securable to a bungey jumper 118. Advantageously, a rigging frame 208 may allow the bungey cord 119 to be securely attached to the jump-off platform 206 and indirectly to the end section 212 of the apparatus to tether or restrict the bungey jumper's range of movement.

In one example, the rigging frame 208 and the jump-off platform 206 may be unibody manufactured.

In another example, the rigging frame 208 and the jump-off platform 206 may be manufactured separately and welded together.

In another example, the jump-off platform 206 may be extendable from the end section 212 in a direction orthogonal to a lengthwise direction of the end section 212. The phrase "lengthwise direction" may refer to a direction of the length of the end section 212.

In yet another example, the jump-off platform 206 may be extendable from the end section 212 in a direction parallel to a lengthwise direction of the end section 212.

In yet another example, the retractable apparatus 204 mounted on the vehicle chassis 202 may include only one section, to which a jump-off platform 206 may be fixedly or movably coupled to the end of the section 212 to provide a jump-off location.

In yet another example, the retractable apparatus 204 mounted on the vehicle chassis 202 may include more than three sections, wherein a jump-off platform 206 may be fixedly or movably coupled to a section that may provide an elevated jump-off location.

The mobile bungey jump apparatus 200 may also comprise a recovery winch arm 220 for recovering the bungey jumper 118 after a bungey jump completes. The recovery winch arm 220 may be coupled to the retractable apparatus 204 and configured to be secured to an end of a recovery cord (e.g. 122 in FIG. 6) having another end securable to the bungey jumper 118.

In one example, the recovery winch arm 220 may be rotatably coupled to the retractable apparatus 204 and actuatable to allow placement of the recovered bungey jumper 118 on the jump-off platform 206.

In another example, the recovery winch arm 220 may be coupled to the end section 212 of the retractable apparatus 204.

In yet another example, the articulated apparatus 204 may be extended underneath the bridge 300 to provide an under-bridge access apparatus.

FIG. 3 and FIG. 4 jointly show a method 500 of operating a mobile bungey apparatus 200. Making reference to FIGS. 3 and 4, FIG. 5 illustrates the same method 500 which may at least include a wheeled chassis (e.g. 202), a retractable apparatus (e.g. 204) mounted on the wheeled chassis (e.g. 202), a jump-off platform (e.g. 206) movably coupled to the retractable apparatus (e.g. 204), and a rigging frame (e.g. 208) fixedly coupled to the jump-off platform. At 500, the method may comprise: at 502, arranging the mobile bungey jumping apparatus 200 at a current bungey site while maintaining the retractable apparatus 204 in a second stowed position (e.g. 204 in FIGS. 2A to 3); at 504, arranging the jump-off platform in a first extended position for bungey jumping (e.g. 206 in FIG. 6); at 506, securing an end of a bungey cord (e.g. 119) to the rigging frame (e.g. 208) and securing another end of the bungey cord (e.g. 119) to a bungey jumper (e.g. 118); at 508, facilitating the jumping of the bungey jumper (e.g. 118) from the jump-off platform (e.g. 206).

With reference to FIG. 3, prior to securing the mobile bungey jump apparatus (e.g. 200) to a current bungey jump site, the method 500 may further include transporting the mobile bungey jump apparatus (e.g. 200) from a previous bungey jump site to the current bungey jump site, which includes arranging the retractable apparatus in a second stowed (e.g. 204) position during the transporting. With reference to FIG. 4, prior to arranging the jump-off platform in a first extended position (e.g. 206) for bungey jumping, the method 500 may further include arranging the retractable apparatus in a second extending position (e.g. 204) to allow the jump-off platform (e.g. 206) in the first extended position for bungey jumping. Arranging the retractable apparatus (e.g. 204) in the second extended position may further comprise: extending the intermediate section (e.g. 210) of the retractable apparatus (e.g. 204) relative to the wheeled vehicle chassis (e.g. 202). The intermediate section (e.g. 210) may be movably coupled to the end section (e.g. 212), which in

turn may be movably coupled to the jump-off platform (e.g. 206). The method of arranging the jump-off platform in the first extended position (e.g. 206) for bungey jumping may comprise slidably extending the jump-off platform (e.g. 206) relative to the end section (e.g. 212). Arranging the jump-off platform (e.g. 206) in the first extended position for bungey jumping may also include slidably extending the jump-off platform (e.g. 204) relative to the end section (e.g. 212).

In one example, the jump-off platform (e.g. 206) may be extended in a direction orthogonal to a lengthwise direction of the end section (e.g. 212).

In another example, the jump-off platform (e.g. 206) may be extended in a direction parallel to a lengthwise direction of the end section (e.g. 212).

FIG. 6 shows a rear view of the exemplary mobile bungey apparatus 200 of FIG. 4, in which a bungey jumper 118 is in a bungey cord retrieval process, according to various embodiments. A winching system may include at least a recovery winch 221 rotatably coupled to the end section 212 of the retractable apparatus 204 and a winch arm 220 rotatably attached to one end of a winch rope 122 to facilitate cord retrieval. The other end of the winch rope 122 is attached to the bungey jumper 118. The winching process may be manually or electrically controlled by the bungey staff 124 to lift or recover the bungey jumper back to the jump-off platform 206 (originally jump-off location). Advantageously, the winch system may allow a bungey jumper 118 to recover to the original jump-off location or may allow the bungey jumper 118 to lower to a safe place after a jump completes.

The method of recovering the bungey jumper 118 may comprise the steps of securing an end of a recovery cord 122 to a recovery winch arm 221 which is coupled to the retractable apparatus 206, and securing another end of the recovery cord 122 to a bungey jumper 118. The recovered bungey jumper 118 may be lifted back onto the jump-off platform 206 by rotatably actuating the recovery winch arm 220. Similarly, the recovered bungey jumper 118 may also be lowered to an under-bridge or an under mobile bungey apparatus safe place. The term “under-bridge” may refer to the space directly under the bridge, excluding the space outside the edge of the bridge.

FIG. 7 shows a schematic top view of the exemplary mobile bungey jump apparatus 200 of FIG. 4, according to various embodiments.

FIG. 8 shows a schematic perspective view of the end section 212 together with the jump-off platform 206 of the exemplary bungey jumping apparatus of FIG. 4, according to various embodiments. One end of the bungey cord 119 may be attached to the bungey jumper 118 and the other end of the bungey cord 119 may be attached to the rigging frame 208 which in turn may be coupled to jump-off platform 206 in manners of unibody manufacturing or welding.

FIGS. 9A, 9B, and 9C show schematic top, front, and rear views of a mobile bungey apparatus 900 in a stowed position, respectively. With reference to FIG. 1, the wheeled chassis (e.g. 102 in FIG. 1) in FIGS. 9A to 9C is adapted from a truck, and the retractable apparatus (e.g. 102 in FIG. 1) is configured to be arranged in a second stowed position when the jump-off platform (e.g. 104 in FIG. 1) is configured to be arranged in a first stowed position for transportation. Advantageously, such a compact configuration of apparatus 200 is arranged for transportation/relocation.

FIG. 10 is a schematic diagram illustrating a rear view of the mobile bungey jump apparatus of FIG. 9C on a cross-sectional view of bridge 300. As seen in FIG. 10, the retractable apparatus 904 may be mounted on the wheeled vehicle chassis 902, and the jump-off platform 906 may be

rotatably coupled to the retractable apparatus 906. When the retractable apparatus 906 is in a stowed position, the jump-off platform 904 is in a stowed position accordingly. In FIG. 10 and the subsequent figures, the stowed position of the jump-off platform 906 is referred to as a first stowed position, and the stowed position of the retractable apparatus 904 is referred to as a second stowed position.

FIG. 11 is a schematic diagram illustrating a side view of the mobile bungey jump apparatus 900 in an extended position. In FIG. 11, the jump-off platform 906 may be rotated 90 degrees along an axis parallel to the lengthwise direction of the wheeled chassis 902, from a first stowed position where the jump-off platform 906 is on top of the wheeled vehicle chassis to a first extended position where the jump-off platform 906 is extended relative to the wheeled chassis 902 for providing the bungey jumper 118 with an off-bridge jump-off location.

FIG. 12 is a schematic diagram illustrating a rear view of the mobile bungey jump apparatus of FIG. 11. As seen in FIG. 12, the retractable apparatus 904 includes a triangle structure having one side with two vertices unmovingly or fixedly mounted to the wheeled vehicle chassis 902 to secure the jump-off platform 906 and a vertex unfixed or movably coupled to the wheeled vehicle chassis 902, and the retractable apparatus 904 is rotatably coupled to the jump-off platform to provide a rotation along an axis parallel to a lengthwise direction of the wheeled vehicle chassis by 90 degrees to transfer the jump-off platform from the first stowed position to the first extended position. In one example, the retractable apparatus 904 may be fixedly coupled to the wheeled chassis 902 and may not be arranged in an extended position.

In another example, a recovery winch arm (not shown) may be coupled to the jump-off platform 906 and configured to be secured to an end of a recovery cord having another end securable to a bungey jumper 118. The recovery winch arm may be rotatably coupled to the jump-off platform 906 and actuatable to allow placement of the recovered bungey jumper 118 on the jump-off platform 906. The rigging frame and recovery winch arm are not shown in FIGS. 9A to 12, but they may be provided at the jump-off platform 906 similar to the embodiments shown in FIGS. 7 and 8.

The main steps in the method of operating the bungey jump apparatus 900 are similar to the method 500 of operating the bungey jump apparatus 200. Different steps relate to prior to arranging the jump-off platform 906 in a first extended position for bungey jumping. The method of operating the apparatus 900 may include rotating the jump-off platform 906 with 90 degrees via a hinge which is coupled to the articulated apparatus, along an axis parallel to a lengthwise direction of the wheeled vehicle chassis 902 to transfer the jump-off platform 906 from the first stowed position (e.g. 906 in FIG. 10) to the first extended position (e.g. 906 in FIG. 12), and wherein the retractable apparatus 904 may remain in the same position as the jump-off platform 906 is in the first stowed position.

The method further includes securing an end of a recovery cord to a recovery winch arm which is coupled to the jump-off platform 906 and securing another end of the recovery cord to the bungey jumper 118.

The recovery winch arm may be rotatably coupled to the retractable apparatus 904, and after facilitating the jumping of the bungey jumper, the method includes rotatably actuating the recovery winch arm to place the recovered bungey jumper 118 on the jump-off platform 906.

While the invention has been particularly shown and described with reference to specific embodiments, it should

be understood by those skilled in the art that various changes in form and detail may be made therein without departing from the spirit and scope of the invention as defined by the appended claims. The scope of the invention is thus indicated by the appended claims and all changes which come within the meaning and range of equivalency of the claims and therefore intended to be embraced.

The invention claimed is:

1. A mobile bungey jump apparatus comprising:
a wheeled vehicle chassis;
a retractable apparatus mounted on the wheeled vehicle chassis for providing a jump-off platform with a first stowed position for transportation or a first extended position for off-bridge access,

the jump-off platform movably coupled to the retractable apparatus and storable substantially within a footprint of the wheeled vehicle chassis when the jump-off platform is in the first stowed position, and extendable from the retractable apparatus when the retractable jump-off platform is in the first extended position for bungey jumping; and

a rigging frame fixedly coupled to the jump-off platform and configured to be secured to an end of a bungey cord having another end securable to a bungey jumper;
wherein the retractable apparatus includes: an intermediate section extendable relative to the wheeled vehicle chassis; and an end section movably coupled thereto, wherein the jump-off platform is movably coupled to the end section.

2. The mobile bungey jump apparatus of claim 1, wherein the retractable apparatus is configured to be arranged in a second stowed position when the jump-off platform is in the first stowed position for transportation, or a second extended position when the jump-off platform is in a first extended position for bungey jumping.

3. The mobile bungey jump apparatus of claim 1, wherein the jump-off platform is slidably coupled to the end section.

4. The mobile bungey jump apparatus of claim 1, wherein the jump-off platform is extendable from the end section in a direction orthogonal or parallel to a lengthwise direction of the end section.

5. The mobile bungey jump apparatus of claim 2, further comprising:

a recovery winch arm coupled to the retractable apparatus and configured to be secured to an end of a recovery cord having another end securable to the bungey jumper.

6. The mobile bungey jump apparatus of claim 5, wherein the recovery winch arm is rotatably coupled to the retractable apparatus and actuatable to allow placement of the recovered bungey jumper on the jump-off platform.

7. The mobile bungey jump apparatus of claim 2, wherein the retractable apparatus includes an under-bridge access apparatus.

8. The mobile bungey jump apparatus of claim 1, wherein the retractable apparatus is mounted on the wheeled vehicle chassis, and the jump-off platform is rotatably coupled to the retractable apparatus.

9. The mobile bungey jump apparatus of claim 8, further comprising a hinge rotatably coupling the jump-off platform to the retractable apparatus, and configured to transfer the jump-off platform from the first stowed position to the first extended position.

10. The mobile bungey jump apparatus of claim 8, wherein the retractable apparatus includes a triangle structure having one side with two vertices unmovingly mounted to the wheeled vehicle chassis to secure the jump-off platform and a vertex unfixed to the wheeled vehicle chassis, and wherein

11

the retractable apparatus is rotatably coupled to the jump-off platform to provide a rotation along an axis parallel to a lengthwise direction of the wheeled vehicle chassis by 90 degrees to transfer the jump-off platform from the first stowed position to the first extended position.

11. The mobile bungey jump apparatus of claim **8**, further comprising:

a recovery winch arm coupled to the jump-off platform and configured to be secured to an end of a recovery cord having another end securable to a bungey jumper.

12. The mobile bungey jump apparatus of claim **11**, wherein the recovery winch arm is rotatably coupled to the jump-off platform and actuatable to allow placement of the recovered bungey jumper on the jump-off platform.

13. A method of operating a mobile bungey apparatus which comprises: a wheeled vehicle chassis; a retractable apparatus mounted on the wheeled vehicle chassis; a jump-off platform movably coupled to the retractable apparatus; and a rigging frame fixedly coupled to the jump-off platform, the method comprising:

while maintaining the retractable apparatus in a second stowed position, arranging the mobile bungey jump apparatus at a current bungey jump site;

arranging the jump-off platform in a first extended position for bungey jumping;

securing an end of a bungey cord to the rigging frame and securing another end of the bungey cord to a bungey jumper; and

facilitating a jumping of the bungey jumper from the jump-off platform; wherein arranging the retractable apparatus in the second extended position includes: extending an intermediate section of the retractable apparatus relative to the wheeled vehicle chassis, wherein an end section is movably coupled to the intermediate section, wherein the jump-off platform is movably coupled to the end section.

14. The method of claim **13**, wherein prior to securing the mobile bungey jump apparatus to a current bungey jump site, the method further comprising:

transporting the mobile bungey jump apparatus from a previous bungey jump site to the current bungey jump site, including arranging the retractable apparatus in a second stowed position during the transporting.

15. The method of claim **13**, wherein prior to arranging the jump-off platform in the first extended position for bungey jumping, the method further comprising:

arranging the retractable apparatus in a second extended position to allow arrangement of the jump-off platform in the first extended position for the bungey jumping.

12

16. The method of claim **13**, wherein the jump-off platform is slidably coupled to the end section, wherein arranging the jump-off platform in the first extended position for bungey jumping includes:

5 slidably extending the jump-off platform relative to the end section.

17. The method of claim **13**, wherein arranging the jump-off platform in the first extended position includes: extending the jump-off platform from the end section in a direction orthogonal or parallel to a lengthwise direction of the end section.

18. The method of claim **13**, further comprising: securing an end of a recovery cord to a recovery winch arm which is coupled to the retractable apparatus and securing another end of the recovery cord to the bungey jumper.

19. The method of claim **18**, wherein the recovery winch arm is rotatably coupled to the retractable apparatus, 20 wherein after facilitating the jumping of the bungey jumper, the method further comprising:

rotatably actuating the recovery winch arm to place the recovered bungey jumper on the jump-off platform.

20. The method of claim **13**, wherein the retractable apparatus includes an under-bridge access apparatus.

21. The method of claim **13**, wherein prior to arranging the jump-off platform in the first extended position for bungey jumping, the method further comprising:

rotating the jump-off platform with 90 degrees via a hinge which is coupled to the retractable apparatus, along an axis parallel to a lengthwise direction of the wheeled vehicle chassis to transfer the jump-off platform from the first stowed position to the first extended position, and wherein the retractable apparatus is remained in the same position while the jump-off platform is in the first stowed position.

22. The method of claim **21**, further comprising: securing an end of a recovery cord to a recovery winch arm which is coupled to the jump-off platform and securing another end of the recovery cord to the bungey jumper.

23. The method of claim **22**, wherein the recovery winch arm is rotatably coupled to the retractable apparatus, wherein after facilitating the jumping of the bungey jumper, the method further comprising:

rotatably actuating the recovery winch arm to place the recovered bungey jumper on the jump-off platform.
